CLAIM

The ornamental design for a payment card with a notch, as shown and described.

DESCRIPTION

FIG. 1 is a back side perspective view of a first embodiment of a payment card with a notch showing our new design.

FIG. 2 is a back side view thereof.

FIG. 3 is a front side view thereof.

FIG. 4 is a top elevational view thereof.

FIG. 5 is a bottom elevational view thereof.

FIG. 6 is a right side elevational view thereof.

FIG. 7 is a left side elevational view thereof.

FIG. 8 is a back side perspective view of a second embodiment of a payment card with a notch showing our new design.

FIG. 9 is a back side view thereof.

FIG. 10 is a front side view thereof.

FIG. 11 is a top elevational view thereof.

FIG. 12 is a bottom elevational view thereof.

FIG. 13 is a right side elevational view thereof; and,

FIG. 14 is a left side elevational view thereof.

The broken lines are illustrative only, presented to show an exemplary layout, and do not form part of the claimed design.
